AUTOMATIC PAPER PUNCHING MACHINE

Charles C. Cruzan, Salt Point, N. Y., assignor to
 Wire-O Corporation, Poughkeepsie, N. Y., a
 corporation of New York

Application April 14, 1948, Serial No. 20,878

12 Claims. (Cl. 164—117)

1

The invention here disclosed relates to paper punching machines and particularly to machines of the type covered by United States Patents 2,114,259 of April 12, 1938, and 2,238,680 of April 15, 1941, for punching the perforations required for securing sheets in wire and plastic binders.

As disclosed in these patents, the sheets are punched, a group at a time, and the handling of these "lifts," as they are called, has required special training and skill on the part of the operator and the output of such machines has depended largely on the skill and attention of the operator.

Primary objects of the present invention are to effect the necessary separating and feeding operations, all automatically, and with an accuracy and speed not dependent upon any individual skill or cooperation.

Special objects are to attain these results at a reasonable cost and with what may be considered relatively simple, mechanical structure adapted to run continuously over extended periods.

Particular objects of the invention also are to provide a machine of the characteristics mentioned which may be readily set up to handle different sizes and grades of paper stock and be otherwise readily adaptable to performing or carrying out different or special required operations.

Other special objects of the invention are to accomplish the purposes outlined without greatly or objectionably increasing the bulk over machines such as heretofore employed in hand feeding operations, thus to enable use of the new automatic machines in binderies having limited space.

Other desirable objects and the novel features of the invention are set forth or will appear in the course of the following specification.

The drawings accompanying and forming part of the specification illustrate a present practical embodiment of the invention. Structure, however, may be modified and changed as regards the immediate illustration, all within the true intent and broad scope of the invention as herein-after defined and broadly claimed.

Fig. 1 in the drawings is a plan view of the machine with parts broken and some parts appearing in section;

Fig. 2 is a broken front elevation of the machine, with the upper tape frame shown in released and partly lifted position;

Fig. 3 is a broken sectional view on a larger scale showing the upper tape frame cammed upward and hooked in its fully lifted position;

Fig. 4 is a broken view of the right-hand end

2

Fig. 5 is a fragmentary detail of the cam and cable connections for operating the jogger cooperating with the end stop;

Fig. 6 is an enlarged broken sectional view on an enlarged scale illustrating particularly the lift gripping rolls, feed tapes, end stop and jogger;

Fig. 7 is a fragmentary part sectional view illustrating details of the cooperating end stop and jogger;

Figs. 8 and 9 are enlarged broken plan and front views, respectively, of the lift feed mechanism showing the feed slide and holdback clamp in retracted position;

Fig. 10 is a broken sectional view showing the slide advanced to push a lift from the bottom of the stack and the holdback clamp closed to hold the overlying sheets in place while the lift is slid out from beneath the same;

Fig. 11 is a broken cross sectional detail of the slide construction as on substantially the plane of line 11—11 of Fig. 10;

Fig. 12 is a perspective view of one of the punched lifts.

Figs. 13 and 14 are plan views of the feeder blade and clamp plate for adjustably securing the same;

Fig. 15 is a broken side elevation on an enlarged scale showing how the under surface of the feed blade or "bayonet" may be relieved to avoid any tendency for jamming or wedging the sheets in the stack.

The punching portion of the machine is shown as of the same general design as disclosed in Patent 2,238,680, with a ram 15 carrying the punches, operating vertically in side guides 16, 17, and actuated by a rocker 18 journaled in the side guides at 19 and connected by a pitman 20 with a crank or cam on the drive shaft 21. A front stop 22, Fig. 1, determines the position of the row of perforations 23 punched in a lift of sheets such as illustrated at 24, Fig. 12.

In the present invention the sheets are stacked in quantity on a table 25 at one side of the feed table 26 directly in front of the punch and fed out from the bottom of the stack, one lift at a time, to the punch mechanism.

In the illustration the sheets 27 are confined in stack formation on the table 25 by upright angled front corner guides 28, 29, and rear guides 30, 31. These may be adjustably mounted to accommodate different size sheets as by being secured by bolts 32 engaged in undercut grooves 33 in the table top.

Separation and feeding of the group of sheets forming the lowermost lift is accomplished in the

illustration by a slide 34 operating over the table top and having a tapered and sharpened forward edge portion 35 spaced above the top a distance 36, Fig. 9, equivalent to the thickness of the lift and therefore adapted to penetrate the stack at the proper level to separate the sheets necessary to form the lower lift 24.

This slide has a feed shoulder 37 at the back of the separating blade portion 35 which, as shown in Figs. 10 and 15, will forward the separated sheets into the bite of a pair of feeding-out rollers 38, 39, Figs. 2 and 6.

As shown in the latter view, the front stack guides 28, 29, are relieved at their lower ends to form a gateway 40 for free passage of the separated lift to the pulling-out rolls 38, 39.

To prevent dislodgement of the sheets overlying the separated lift, the feed slide is provided with means for holding back the next adjoining overlying layer of sheets in the form of a clamp 41 having a tapered and sharpened forward edge 42 to penetrate the stack at a level above the separated lower layer and pivoted at 43 to close down in gripping engagement with the thus separated upper layer of sheets.

The closing, automatic gripping engagement of the holdback clamp is effected, in the illustration, by providing it with an inclined cam shaped upper surface 44 to engage the lower edge 45 of a bar 46 extending across between the rear stack guides 30, 31.

To allow the feed slide the forward movement necessary to feed the separated lower lift after the upper layer has been gripped and held by the holdback clamp, the latter is shown mounted on a plate 47 slidably mounted at 48 in the main feed slide 34.

The pivot 43 for the holdback clamp is shown carried by lugs or ears 49 on the slide plate 47 and the latter is shown projected forwardly on the main slide by a compression spring 50 surrounding the rod 51 and bearing against the forward end of a guide sleeve 52 adjustably secured by clamp screw 53 on the main slide.

By releasing the set-screw 53 and longitudinally adjusting guide sleeve 52, the tension of spring 50 may be adjusted to hold the clamp advanced under proper spring pressure to enter the stack sufficiently for a firm grip on the layer of sheets overlying the sheets forming the separated lower lift.

The holdback clamping blade 41 is yieldingly held in open or raised position, as in Figs. 2 and 9, by a spring 54 bearing downward on the outwardly extended arm 55 of this member and adjusted as to tension by the overstanding thumb-nut 56.

It will be noted in Fig. 9 that the under surfaces of both the lower separating blade 35 and the upper clamping blade 41 are substantially parallel with the table to enter the stack smoothly without tearing the sheets and that the upper surfaces are inclined to act in a wedging capacity for lifting and separating the sheets.

The under surface of the lower, separating blade 35, however, preferably is relieved, back of the front end portion of the same, substantially as indicated at 35a in the detail view, Fig. 15, all the way back to the feed shoulder 37 so as to overcome any tendency for the separated lift forming sheets 24 wedging against the face of the blade. This wedging tendency may be created by a slight springing of the thinned projecting portion of the blade away from and out of parallelism with the face of the table. The relief in

the under surface of the blade affords slight additional clearance for the sheets back to the feed shoulder and effectually prevents any wedging or jamming of the sheets beneath the blade.

The lift separating and holdback members 35 and 41 are carried, in the present disclosure, by a sliding carriage made up of bars 57, Fig. 11, operating in guide slots 58 in the table 25 and secured by through bolts 59 to the body portion 34 of the feed slide at the top, and to the underlying slide plate 60 and operating plate 61 at the bottom, beneath the table.

The latter, as shown in Fig. 2, carries a wrist-pin 62 engaged by one end of a link 63 whose opposite end is pivotally connected at 64 with the upper end of a lever 65 pivotally supported at its lower end at 66 and carrying a roller 67 in engagement with the groove 68 in a cam 69.

The cam 69 is driven in timed relation with the punch mechanism, in the present disclosure by a chain drive 70, Fig. 4, from the main drive shaft 21 of the punch to a parallel shaft 71, connected by bevel gearing 72 with the shaft 73 on which the cam is mounted.

This particular form of drive imparts a constant stroke to the lift feed mechanism. To enable adjustment of this mechanism to the size of sheet being handled, the slide bars 57 are shown in Fig. 9 as having a series of openings 74 therethrough for the bolts 59 spaced longitudinally of the bars so that the body or base portion 34 may be secured at different positions on the slide carriage, closer to or further removed from the stack.

For finer adjustments the paper feeder is secured on the slide carriage through the intermediacy of a clamp plate 75 slotted at 76 for passage of the through bolts 59, the base 34 having longer slots 77 for these bolts.

Outer sets of bolts 78 serve to further secure the clamp plate to the base plate 34, these bolts being shown arranged in pairs and applying pressure through the pads or washer-like clamp plates 79. The main clamp plate 75 is shown as having elongated slots 80 in its outer edges for the free passage of the pairs of bolts 78.

It will be seen that upon loosening bolts 59 and 78 the clamp plate 75 is released to permit bodily adjustment of the sheet feeder base 34 in respect to the bars 57 of the slide carriage, to the extent permitted by length of the slots 77 and 80. Spacer ribs 81 on the under side of the base plate 34 operating through the slots 82 in the table top directly engage the tops of the slide bars 57 so that tightening of the bolts 59 secures the plate 34 without binding it on the table.

Flat springs 83 are shown in Figs. 8 and 9 held beneath the heads of the inner sets of bolts 59 and bearing downward at their free ends on the forwardly or inwardly projecting portion of the feeder plate 34 to prevent vibration and hold it down in smooth sliding engagement with the surface of the table.

The bottom lift 24, separated as described and pushed out from beneath the layer of sheets held back above the same into the bite of the constantly running feed rollers 38, 39, is advanced by the latter into the grip of the constantly running upper and lower companion feed tapes 84, 85, operating over the feed table 26 in front of the punch. The upper set of tapes 84 are shown carried by pulleys 86, 87, on shafts 88, 89, and the lower set of tapes on pulleys 90, 91, on shafts 92 and 93.

A special feature of the upper set of tapes is that they are mounted in a swinging frame 94

pivoted at 95 on an axis corresponding to the axis of the upper feed roll shaft 88, Figs. 2 and 3, so that this complete set of tapes, as a single unit, may be swung upwardly clear of the lower tapes and so as to fully uncover the punch table.

To accomplish complete separation of the tapes the pivots 95 for the upper tape frame are arranged directly on the ends of the sliding journal boxes 96 for the upper roll shaft 88 and the frame is provided with inclined hook shaped cams 97 which by engagement over rolls 98 at the upper sides of said journal boxes will effect lifting of the structure to an extent substantially as indicated in Fig. 3. The inclined lifting cams 97 are shown as terminating in hook portions 98a fitting over the rolls 98 to retain the parts in this position against the tension of the springs 99 operating to lower the journal boxes to effect cooperative engagement of the upper tapes 84 with the lower tapes 85.

With this construction the feed table in front of the punch may be entirely cleared at any time by simply swinging the upper tape frame 94 upwardly in the manner indicated in Fig. 2, into the substantially vertical position shown in Fig. 3, where it will be releasably held so long as may be desired, by engagement of the hook cams 97, 98a over the supporting rollers 98, and in which relation the upper tapes, though they may continue to run, because of gear 108 still remaining in mesh with gear 107, will be free of the lower tapes.

The drive for the upper and lower sets of tapes is provided in the machine illustrated by belt drive connections 100 from the motor 101, Fig. 1, which operates the punch mechanism, to a horizontally extending shaft 102 carrying a spiral gear 103 in mesh with a corresponding gear 104 on the intermediate, back to front shaft 105, Fig. 2, carrying a gear 106 in mesh with a gear 107 on the lower tape drive shaft 92, gear 107 being in mesh with a gear 108 on the end of the upper tape drive shaft 88.

Gear 106 also as shown in Fig. 2, is in mesh with a gear 109 on the end of the shaft 110 carrying the lower feeding-out roll 38, and this gear 109 is in mesh with the gear 111 on the upper feeding-out roll shaft 112.

Thus a single cross shaft 105 is utilized to drive the feed rolls 38, 39, as well as both sets of lower and upper feed tapes.

To assure passage of the separated lift from the pulling-out rolls 38, 39, to the feed tapes, a guide 113, Fig. 6, is shown interposed between the rolls and the entrance end to the feed tapes.

The lift of sheets 24 advanced by the feed tapes 84, 85, over the front of the punch table 26, is stopped in proper position in front of the punch dies by an end stop 114, Figs. 1, 2, 6 and 7, projected upwardly past the feeder tapes by rocker arms 115 on a rock shaft 116 oscillated by lever arm 117 and link 118 from a rock lever 119 pivoted at 120 and carrying a follower roll 121 in engagement with a cam surface 122 on the edge of the cam 69.

A spring 123 connected with the lever 119 acts to yieldingly hold the lever rocked into position with the end stop uplifted as in Fig. 6 and the lower roll 121 in engagement with the edge cam 122.

To register the sheets of the lift accurately against the end stop 114, a jogger 124, Fig. 7, is provided in the form of a lever pivoted at 125 on a slide 126 actuated by a lever 127 projecting upwardly from a shaft 128 rocked by a spring 75

129 in a direction to advance the jogger, to the left in Figs. 6 and 7, and shifted in the opposite direction by a pull cable 130 connected with an arm 131 on the shaft and extending over a pulley 132 to one end of a rock lever 133, Figs. 4 and 5, pivoted at 134 and carrying at the opposite end a roller 135 in engagement with an edge cam 136 on the shaft 71.

The pivotal mounting of the jogger 124, as will be clear from Fig. 7, enables it to yield downwardly to a lift of sheets passing over the top of the same and to rise in back of the rearward edge of the lift, assisted by a spring 137. The cam 136 is timed to withdraw the jogger 15 at a time when the lift is due to engage the end stop 114 and to then permit the jogger to come up against the back edge of the lift under pull of the spring 129. To permit necessary adjustments of the jogger, the same is shown carried by a bracket 138 in Fig. 7, adjustably secured at 139 on the actuating slide 126.

The lift of sheets fed into position and registered by the jogger 124 in front of the press, is fed into position beneath the punches by a gage or jogger 140, Fig. 1, carried by a bar 141 slidably guided in the machine and carrying a roll 142 at the back in engagement with a cam 143 on the main drive shaft 21. This reciprocating bar is acted on at the front by a spring 144 and the parts are timed for this gage 140 to shift the sheets after they are registered against the end stop 114 inwardly against the front stop 22 of the punch.

The front jogger 140 is shown in Fig. 1 as having an inwardly convergent guiding edge 145 for truing up any out of line sheets as they are advanced by the tapes into position for feeding into the punch.

The end stop 114 remains in upraised position while the front gage or jogger 140 is feeding the lift of sheets across the face of the end gage into the registered position in the punch, but as the punch head comes down and the sheets are perforated, this end stop may be lowered so that the lift will be free and ready to be fed by the tapes laterally out of the punch as soon as the punch head lets go of the perforated sheets.

Thus no time is lost and only a momentary stoppage of the lift occurs, just long enough for the sheets to be jogged, shifted laterally to the punch gage and punched, the constantly running tapes taking control and feeding the lift on out of the machine as soon as the punching is completed.

Actually the jogger 124, after registering the lift against the end stop 114, may rest while the lift is shifted laterally by the front jogger 140 into the punch and then, after the punch releases the stock, be advanced to start the lift out of the punch, thus to assist the tapes in carrying the punched lift on out of the machine. This is of advantage particularly in the case where the punches leave burrs at the edges of the perforations which might tend to cause the sheets to stick to the punches, assuring that the lifts will positively start and be fed away by the tapes.

To prevent the layer of sheets overlying the bottom lift from shifting forward under the impulse of the clamping blade entering the stack, a so-called "gate" is provided in the illustration in the form of a bar 150, Figs. 1, 2, 4 and 6, adjustably mounted on the cross bar 151 between the front stack guides 28, 29, by a bolt 152 and

thumb screw 153. The cross bar 151 is shown as horizontally slotted at 154 and the gate as vertically slotted at 155, Fig. 4, for passage of the bolt 152, allowing for both lateral and vertical adjustment of the gate. Set screws 156, Fig. 4, at the sides of the gate and bearing on top of the bar 151, provide for accurate vertical adjustments of the gate substantially to meet the lower edge of the held back group of sheets overlying the bottom lift. Adjusted with its lower edge substantially at the parting line between the lower lift and the layer gripped by the holdback clamp, the gate assists this clamp in holding back the overlying layer of leaves and forms an abutment which will prevent forward shifting movement of this layer under the push of the clamp blade in entering the stack.

The gate 150 also is important in holding back the overlying covers in the case where the machine is used for feeding covers instead of lifts of sheets to the punch mechanism, the adjustments described being utilized to accurately set the gate for such purposes.

The upper feed tapes 84 may be variably tensioned toward the lower set of tapes, in the machine shown, by adjustment of the thumb screws 157, Fig. 6, forming the abutments for the hold-down springs 90.

In similar fashion the upper feed roll 39 may be journaled in vertically slidable boxes tensioned by springs 158 held by thumb nuts 159. The independent adjustment of these thumb nuts at opposite ends of the roll is particularly advantageous when setting up the machine to handle sheets, covers or the like of different widths, it being desirable many times under such circumstances to apply greater tension at one end than at the other end of this feed roll.

The gage 140 which feeds the lifts into the punch is shown in Fig. 1 as adjustably secured at 146 on the reciprocating bar 141 so that it may be set to different width sheets. In the illustration the sheets being punched are of relatively small size. The adjustments of the various parts are such, though, that a wide range of sheet sizes may be accommodated in the same machine.

The lifts, as fast as they are released by the punch mechanism, are fed out by the tapes onto a suitable stacker such as indicated at 147, Figs. 1 and 2, at the far end of the machine beneath the delivery end of the tapes and piled in the same order they were in in the supply stack, an important feature in handling numbered sheets, successive leaves of books or the like.

Operation

Reviewing briefly, the sheets 27 confined in stack formation by stack guides 28, 29, 31, Figs. 1 and 2, are removed, one lift at a time, from the bottom of the stack by a sliding feeder 34 having a blade 35, Figs. 5, 9 and 10, to enter the stack at the proper lift level and an abrupt shoulder 37 beneath and at the back of said blade to feed out the separated lift into the bite of the constantly running feeding-out or pulling-out rolls 38, 39, Fig. 6.

The sheets above the separated lift are gripped and held by a second blade 41 on the feed slide which enters the stack above the bottom lift and closes down into gripping engagement on the overlying sheets as it rides under the cam bar 45, Fig. 10. This holdback clamp being carried by the bar 47 slidably mounted on the main slide base 34, remains in gripping engagement with

the sheets while the feed slide continues and completes its inward feeding movement.

The lift taken by the feeding-out rolls 38, 39, Fig. 6, is immediately advanced into the grip of the companion feed tapes 84, 85, and by the latter carried up to the end stop 114. As the lift reaches this stop the jogger 124 comes up behind the back edge of the lift and registers or insures their squaring up against the end stop 114.

As registration is effected the reciprocating jogger 140, Fig. 1, feeds the lift laterally into engagement with the front stop 22 of the punch. The punch may be operated at relatively high speed so that the dwell for punching need be momentary. To maintain or assist in maintaining the desired high speed operations, the end stop 114 may be lowered practically as soon as the punch takes hold of the paper so that when the punch in its retractive movement lets go, the lift is immediately carried on out of the machine by the tapes. The tapes run constantly and so are ready at all times to take the lifts from the feeding-out rolls 38, 39, advance them to the punching station and then carry them clear of the punch mechanism. These tapes are tensioned to grip the lifts firmly enough to effect these operations but with sufficient slip to permit momentary dwell of the lifts while they are being registered against the end stop 114, then shifted laterally into the punch and arrested there for the punching stroke.

The lifts and the sheets composing the lifts are held under proper control at all times. The entire automatic operations are rapid and accurate, the machine is of compact design and does not require much more space than the machines of the semi-automatic type first mentioned. All parts are readily accessible for necessary adjustments or substitution.

While the machine is primarily designed for separating and feeding sheets in lifts as described, it is realized that the machine may be used for such purposes as punching book covers or the like, and in which event a plain feed slide which will feed one or more covers from the bottom of the stack may be used in place of the lift separating blade and holdback clamp structure illustrated.

As the stack lowers in the hopper, from the feeding out of the stock from the bottom, the stack may be replenished by simply adding fresh sheets to the top of the stack. The operation may thus be a continuous one and, since the machine can operate at high speed, high rates of production can be maintained. While the lowering of the end stop 114 prior to the release of the lift by the punch contributes to the high speed action and may be a preferred method of operation, it is contemplated that this stop may be timed to let go the lift substantially at the same time as the punch.

While the invention is of particular importance for perforating sheets and for that reason has been so disclosed, it should be understood that the invention is of broader scope and has many other applications as, for example, in connection with machines for trimming and for cutting the round corners on sheets. The terms employed herein have therefore been used in a descriptive rather than in a limiting sense and are to be read accordingly except where the intent to restrict is plain or possibly where state of the prior art may impute a limiting sense.

What is claimed is:

1. A paper feed device for an automatic paper punching machine having a punch for perforating a lift of sheets and comprising feed tapes running across the front of said punch, means for supporting a stack of sheets at the entrance end of said feed tapes, means for separating, feeding out and delivering a lift of sheets from the bottom of the stack to said feed tapes, an end stop for stopping a lift of sheets advanced by said feed tapes in line with the punch, means for feeding a stopped lift of sheets laterally of the feed tapes into the punch and means for shifting the stop clear of a lift perforated by the punch.

2. A paper feed device for an automatic paper punching machine having a punch for perforating a lift of sheets and comprising feed tapes running across the front of said punch, means for supporting a stack of sheets at the entrance end of said feed tapes, means for separating, feeding out and delivering a lift of sheets from the bottom of the stack to said feed tapes, an end stop for stopping a lift of sheets advanced by said feed tapes in line with the punch, means for feeding a stopped lift of sheets laterally of the feed tapes into the punch, means for shifting the stop clear of a lift perforated by the punch and a jogger for registering the lifts against said stop.

3. A paper feed device for an automatic paper punching machine having a punch for perforating a lift of sheets and comprising feed tapes running across the front of said punch, means for supporting a stack of sheets at the entrance end of said feed tapes, means for separating, feeding out and delivering a lift of sheets from the bottom of the stack to said feed tapes, an end stop for stopping a lift of sheets advanced by said feed tapes in line with the punch, means for feeding a stopped lift of sheets laterally of the feed tapes into the punch and means for shifting the stop clear of a lift perforated by the punch, said lift separating, feeding-out and delivering means including a feed blade entering the stack at the bottom lift level and a holdback clamp for gripping the immediately overlying sheets when the bottom lifts are being shifted from beneath the same.

4. A paper feed device for automatic paper punching machine having a punch for perforating a lift of sheets and comprising feed tapes running across the front of said punch, means for supporting a stack of sheets at the entrance end of said feed tapes, means for separating, feeding out and delivering a lift of sheets from the bottom of the stack to said feed tapes, an end stop for stopping a lift of sheets advanced by said feed tapes in line with the punch, means for feeding a stopped lift of sheets laterally of the feed tapes into the punch and means for shifting the stop clear of a lift perforated by the punch, said lift separating, feeding out and delivering means including a reciprocating slide having a feed blade penetrating the bottom of the stack and a clamp blade positioned to enter the stack above the feed blade and yieldably mounted on the slide.

5. A paper feed device for an automatic paper punching machine having a punch for perforating a lift of sheets and comprising feed tapes running across the front of said punch, means for supporting a stack of sheets at the entrance end of said feed tapes, means for separating, feeding out and delivering a lift of sheets from the bottom of the stack to said feed tapes, an end stop for stopping a lift of sheets advanced by

said feed tapes in line with the punch, means for feeding a stopped lift of sheets laterally of the feed tapes into the punch and means for shifting the stop clear of a lift perforated by the punch, said lift separating, feeding out and delivering means including a reciprocating slide having a feed blade penetrating the bottom of the stack and a clamp blade positioned to enter the stack above the feed blade and yieldably mounted on the slide and a stationary member engaged by said clamping blade to close the same downwardly into gripping engagement with sheets above the feed blade.

6. A feed device for an automatic paper punching machine having punch mechanism comprising a stack supporting table at one side of said punch mechanism, stack guides on said table, a reciprocating sheet feeder on said table at the outer side of said stack guides, gripper rolls at the base of the stack at the opposite side of said stack guides, a conveyor extending from said gripper rolls in front of said punch mechanism and means for delivering sheets from said conveyor to said punch mechanism, said conveyor including companion feed tapes and a reciprocating stop timed to arrest sheets advanced by said tapes in position to be shifted by said feeding means into the punch mechanism.

7. Apparatus for feeding sheets to an automatic punch comprising, companion feed tapes operating in front of the punch, means for shifting sheets advanced by said tapes laterally to said punch, one set of said companion feed tapes being mounted in a swinging frame pivotally supported at one end and a hook cam at said pivotally supported end for lifting and supporting said frame with the tapes carried thereby separated from the companion tapes.

8. Feed mechanism for an automatic punch, comprising upper and lower sets of companion feed tapes operating across the front of the punch, a frame pivotally supported at one end and carrying the upper set of feed tapes, a hook cam at the pivotally supported end of said frame and a relatively stationary member positioned for engagement by said hook cam.

9. In a machine of the character disclosed, companion sets of upper and lower feed tapes, drive shafts for said tapes having intermeshing gears, vertically slidable journal boxes for the upper drive shaft, a frame for supporting the upper set of tapes pivotally engaged on said journal boxes, a hook cam carried by said frame and a fixed support positioned to be engaged by said hook cam to effect lifting movement of said journal boxes and said upper tape frame.

10. Feed mechanism for an automatic punching machine comprising means for supporting a stack of sheets in front of and at one side of said punching mechanism, sheet conveying means running from the base of said stack across the front of said punching mechanism, means for feeding sheets out from the bottom of said stack and delivering them to said conveying means, means for temporarily stopping sheets on said conveying means in front of said punching mechanism and means for shifting the stopped sheets laterally of said conveying means to said punching mechanism.

11. Feed mechanism for an automatic punching machine comprising means for supporting a stack of sheets in front of and at one side of said punching mechanism, sheet conveying means running from the base of said stack across the front of said punching mechanism,

11

means for feeding sheets out from the bottom of said stack and delivering them to said conveying means; means for temporarily stopping sheets on said conveying means in front of said punching mechanism and means for shifting the stopped sheets laterally of said conveying means to said punching mechanism, said stopping means including a sheet stop and means for shifting the same into the path of movement of sheets carried by said sheet conveying means and then removing the same from said path at the completion of each punching action of said punching mechanism.

12. A sheet feeder of the character disclosed comprising a hopper for confining a stack of 15 sheets, a feed blade reciprocating at the foot of said hopper for feeding sheets out from the bottom of the hopper, a continuously running sheet conveyor for advancing sheets removed from the bottom of the stack, a stop for arresting sheets on 20 said conveyor, means for intermittently operating on sheets arrested by said stop, means for retracting the stop to enable sheets to be continued in

movement by the conveyer after being acted upon by said intermittently operating mechanism and a jogger for registering sheets on the conveyer against said stop and timed to impart starting movement to said sheets after retraction of said stop.

CHARLES C. CRUZAN.
